MAGNETIC PICKUP

Maximilian Weil, New York, N. Y.

Application September 4, 1936, Serial No. 99,365

21 Claims. (Cl. 179—100.41)

My present invention relates to magnetic pickups for phonographic reproduction.

As conducive to a clear understanding of the invention, it is noted that the moving armature mass of magnetic pickups generally has a natural frequency of vibration within that audible frequency range required for satisfactory performance, with consequent marked damping out of frequencies above that of resonance. Rapid changes in amplitude of frequency in the normal use of such device due to its considerable inertia result in a distorted performance, commonly described as "hang-over." While damping of the armature movement alleviates these difficulties to some extent, great increase in stylus-point impedance is thereby entailed, with consequent reduction in the efficiency of the unit and marked increase in the wear and tear on the sensitive record groove.

Among the objects of the invention are to provide a magnetic pickup unit, the performance of which approximates that of the highly developed microphone used in recording, so that the output of said pickup is practically indistinguishable from the original performance as recorded.

Another object is to provide an instrument of the above type, which is simple, sturdy and compact in construction, and in which the inertia of the moving system is so low that its natural frequency is outside, preferably beyond that of the useful range of audibility, with consequent uniform delicacy of response substantially throughout the effective audible range.

Another object is to provide an instrument of the above type, in which the light moving mass is mounted effectively to control the flux through the magnetic elements without weaving or wobbling and in which the resistance imposed to vibration is so slight that the weight resting on the record, and the wear on the record groove are greatly reduced.

Another object is to provide an instrument of the above type which requires no adjustment in use for adaptation to various types of renditions and which maintains its initial sensitiveness and efficiency for long periods of use.

According to the invention, the vibratory system of the instrument, that is, the vibrating magnetic element and associated moving parts by which the flux is controlled in synchronism with the vibrations imposed by the record upon the stylus is greatly reduced in inertia. To this end, the magnetic circuit is so contrived that a fixed magnetic element having only a small fraction

of the mass of the usual armature actually oscillates, and serves as a magnetic flux-relay piece, the relatively greater bulk and mass of the armature proper being anchored against vibration.

In a desirable construction, the magnetic flux relay piece is positioned in the gap between the field poles and the armature and is carried preferably by a non-magnetic extremely light shaft supported in the casing and carrying the stylus. The predominating part of the mass of the vibratory assembly is the stylus itself, the rest of the parts being extremely light in mass and moving in low friction bearings, while the stylus itself is preferably of special construction, affording a minimum of mass at its point and end with the major portion of its small mass at the central clamped portion thereof.

In the accompanying drawing in which are shown one or more of various possible embodiments of the several features of the invention,

Fig. 1 is a perspective view of the completely assembled unit.

Fig. 2 is a view in longitudinal cross section thereof taken on line 2—2 of Fig. 1 and on a larger scale.

Fig. 3 is a plan view of the device with the cover removed, parts being shown in section,

Fig. 4 is a transverse sectional view taken on line 4—4 of Fig. 2,

Fig. 5 is a transverse cross sectional view taken along the line 5—5 of Fig. 2,

Fig. 6 is a perspective view of the pole pieces and armature in correlated position,

Fig. 7 is a perspective view of the magnetic flux relay assembly,

Fig. 8 is a perspective view of the stylus shown in the embodiment of Figs. 1 to 7,

Fig. 9 is a fragmentary view in longitudinal section of the forward end of the casing showing an alternative stylus,

Fig. 10 is a perspective view of the stylus shown in the embodiment of Fig. 9,

Fig. 11 is a fragmentary detail view of a modification, and

Fig. 12 is a similar view of another modification.

Referring now to the drawing, the pickup comprises a casing including a base 10 specially molded to accommodate the parts mounted therein and hereinafter described, and equipped with a sheet metal cover 11 telescoped over the sides thereof and preferably tapering downward at its front as at 12 and attached by screws 13. The shank 14 of the casing has terminal sleeves 15 therein for the terminal members 16 protruding

therefrom, from which insulated conductors 17 lead to the electro-magnetic coil 18 known as the voice coil.

Upon the base is mounted the horseshoe magnet 19 closely fitting against the sides of the base and contacting at the forward end of its legs, the magnetic pole pieces 20 and 21 which are attached to the base by means of screws 22 countersunk in the underface of the base 10. The magnet is retained in place by means of a leaf spring 23 preferably of copper alloy reacting at its ends against shoulders 24 molded in the base, with a central bowed part reacting against the extremity of the horseshoe magnet, and pressing it forward against the pole pieces. Preferably the spring is longitudinally slit at 25 on a level with the upper face of the magnet and the strap 26 determined thereby is pressed forward to overlap the magnet and retain it against the base 10.

The pole pieces are preferably U-shaped as shown with their upper legs or ledges 27 aligned, but spaced from each other as shown, and their lower legs or ledges 28 similarly aligned and spaced. The space determined between said ledges of the facing pole pieces accommodates the coil 18.

A fixed armature piece 29 extends downward centrally of the coil, as shown, is symmetrically spaced from the upper ledges 27 of the pole pieces and its lower end is slightly above the lower ledges 28 of the pole pieces. Said fixed armature is mounted by screws 30 to a plate 31 of non-magnetic material, which, in turn, is attached by means of screw 32 to the upper ledge of the pole piece 20. While the specific construction and arrangement shown is preferred, it is manifest that the coil could be disposed to encircle any part of the magnetic circuit other than the armature, if desired.

The magnetic flux relay comprises an extremely light piece of magnetic material, including a shank 33 with an upstanding flattened wing 34 the latter disposed centrally between the lower ledges 28 of the pole pieces, preferably to protrude slightly above ledges 28 and slightly below the lower extremity of the fixed armature 29 so as to determine small predetermined air gaps with respect to said three pieces, as best shown in Fig. 4. This relay piece is mounted by frictionally fitting its shank 33 into a shaft or tube 35 of extremely light material, preferably of the alloy known as "Duralumin," which extends longitudinally of the base piece and is mounted in bearings 36 and 37 at opposite ends thereof. Preferably, rubber bushings 38 encircle the ends of the tube, which are mounted upon the base, by bearing cap pieces 39 attached to the base by screws 40.

In order to maintain the wing piece 34 normally in properly centered position, the sleeve 35 is provided with an upstanding pin or stud 41 fixed therein, with a flattened upper extremity 42 extending into a corresponding notch 43 on a stop piece 44 fixed by screws 45 upon a corresponding ledge 46 molded in the base 10.

The stylus 47 extends transversely through corresponding apertures 48 in the base 10 and apertures in sleeve 35 and bearing 37 and is clamped at its median portion against the wall of the tube apertures by means of a set screw 50 extending through the forward end of the base 10 and threaded into the forward end of the tube 35.

While the stylus may be of conventional construction, it is preferred to employ the structure

shown in Fig. 8 in which the main shank of the stylus is of conventional diameter, but the pointed end 51 thereof is not the ordinary conical point but is concave longitudinally as shown, for reduction of mass and for effecting a particularly sharp point. Moreover, the upper part 52 of the stylus is of greatly reduced diameter for further reduction in mass. By this construction, those parts of the stylus, namely, the parts near the lower and upper ends, which perform the major movement in operation, are of greatly reduced mass, while the major part of the mass is that intermediate portion in the region clamped by the set screw 50 which performs relatively slight movement, whereby the inertia of the stylus is effectively reduced. Preferably the stylus is inserted through an aperture 53 in the cover 11 and its position is thus accurately determined as shown in Fig. 2, by bringing the upper end of the stylus flush with the outer wall of the cover 11.

The entire assembly of "Duralumin" tube and magnetic flux relay as shown in Fig. 7 is of almost negligible weight, as little as 1½ grains, the preponderating inertia of the vibratory parts in the device residing in the stylus 50 in a preferred construction.

In use of the device on the conventional laterally cut disk record, it will be seen that the vibrations of the stylus point 51 effect corresponding rocking of the tube 35 in its bearings 36 and 37 against the resiliency of rubber bushings 38 which act to damp the vibration, and the wing piece 34 of the magnetic relay in partaking of this movement causes corresponding variations in the air gaps and controls the variations and alternations of magnetic flux between the pole pieces 20 and 21 in manner readily understood by those skilled in the art. As is clear to those skilled in the art the construction may readily be embodied for use with hill and dale records.

The sensitiveness of the device is a consequence of the fact that it is not a relatively heavy armature which is to move in response to the vibrations of the stylus, but the control of magnetic flux is effected by the extremely light moving element 34 which is not an armature properly speaking, but may be properly designated a magnetic flux relay piece the movement of which determines the course of flux of magnitude greater than that which traverses the relay piece itself. The natural frequency of the vibratory system is beyond the effective range of audible frequencies. The course of the magnetic flux is substantially confined as is obvious to the magnet, its pole pieces, the stationary armature, the relay piece and the air gaps therebetween, and in no-wise reaches the stylus 50, since the intervening tube 35 is desirably of non-magnetic material as set forth.

In the embodiment of Figs. 9 and 10 is shown a modification of stylus 50' which illustratively is flattened near its upper end as at 55 to afford a stop resting against the upper portion of the forward bearing 37' of the tube 35' so that it is positively positioned with respect to the tube, as distinguished from the mode of positioning previously described and resorted to in the embodiment of Fig. 2.

It is, of course, understood that the width of the notch 43 is such as to permit the magnetic relay wing 34 to move laterally in the gap between the pole pieces without ever touching either of said pole pieces and the resilience of the rubber bushings 38 serves properly to return the wing piece 34 to the correctly centered

position shown in Fig. 4, so that no bias occurs toward one or the other pole in the absence of impulse applied through the stylus. If damping in addition to that afforded by resilient bushings 5 38 is required, this can conveniently be afforded by rubber stops (not shown) interposed in the space between stud extremity 42 and the walls of notch 43 in stop piece 44.

It is important in the initial assembly of the 10 device that the magnetic relay wing piece 34 be correctly centered between the two pole pieces and that it be correctly spaced from the lower end of the armature piece 29. For this purpose, resort may be had to a two-prong fork (not 15 shown) of width snugly to fit between the pole pieces and which has a space between its tines snugly to straddle the thickness of the wing piece 34. The distance of the magnetic flux relay 20 wing piece 34 from the armature 29 is determined by applying the armature after the pole pieces 25 and flux relay wing have been positioned as described. The armature piece is first caused to engage the upper edge of the wing piece 34 which result may be readily accomplished by loosening fastening screws 30 and moving the armature up or down slightly along its elongated screw slots 30' until such adjustment has occurred.

Thereupon a shim 56 of suitable thickness, 30 desirably in the order of .003" in thickness, is interposed between the mounting plate 31 and the pole piece 28 whereupon the screws 30 are tightened and the desired distance between the armature piece and the relay piece viz. that of the 35 shim thickness is thus readily and accurately determined.

The embodiment of Fig. 11 shows a refinement in the correlation between the armature 29' and the flux relay wing 34'. In this case the armature is shown with a concave lower end 60 so 40 that in the vibratory movement of the flux relay piece the width of the air gap with respect to the armature will vary, decreasing in a direct ratio with the amplitude of the vibration. By this expedient the reluctance of the magnetic circuit 45 automatically decreases with the lower frequencies which correspond to the wider amplitude of vibration so that the low pitched notes are correspondingly accentuated, thereby to compensate for the reduction in the amplitude 50 of low pitched notes on the record frequently made necessary by the close spacing of the spiral convolutions.

Fig. 12 shows another alternative embodiment 55 in which the armature 29' is provided with a fork end presenting parallel lugs 61 and 62 between which the flux relay 34' extends. As will be seen in this case also the air gap between the armature and the flux relay will also decrease in a direct ratio of the amplitude of vibration to 60 perform an effect corresponding to that accomplished by the embodiment of Fig. 11.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the 70 above description or shown in the accompanying drawing shall be interpreted as illustrative and 75 not in a limiting sense.

Having thus described my invention, what I claim as new and desire to secure by Letters Patent is:

1. A magnetic pickup having substantially fixed magnetic parts with an associated voice coil and a vibratory magnetic part, a stylus, a non-magnetic connection between the stylus and the vibratory magnet part, said connection comprising a metal tube having bearings near its opposite ends including resilient bushings, 5 the major portion of the mass of the vibratory parts being contiguous to the axis of rotation of said tube, the mass of the vibratory parts including the stylus, the vibratory magnet part and the connection therebetween having a natural 10 frequency of vibration beyond the effective range 15 of audibility.

2. A magnetic pickup comprising a casing, a magnet therein having a pair of pole pieces, an electromagnetic coil associated therewith, a fixed 20 armature extending into said coil to the vicinity of said pole pieces, a magnetic flux relay piece intervening between said pole pieces and near said armature, a carrying shaft therefor below said pole pieces and perpendicular to the axis 25 thereof, and a stylus carried by said shaft and mechanically connected thereby to said flux relay piece.

3. A magnetic pickup comprising a casing having a fixed magnet therein with a pair of pole 30 pieces with upper and lower ledges, a voice coil housed between said pole pieces, a fixed armature extending between said pole pieces into said coil and terminating above the lower ledges of said 35 pole pieces, and a flux relay extending between said pole ledges contiguous to said fixed armature and a stylus and a shaft at right angles to the axis of said coil and mechanically connected to said flux relay.

4. A magnetic phonograph reproducer comprising a magnet having U-shaped pole pieces with facing legs, a voice coil symmetrically housed therein, a fixed armature extending through the air gap between one pair of legs of the pole pieces and terminating at its lower and 45 contiguous the other air gap, a magnetic flux relay piece extending symmetrically in said latter air gap and contiguous to the armature end, a stylus and rigid means at right angles to the axis of said coil and mechanically connecting the 50 stylus to said flux relay piece.

5. A magnetic pickup comprising a base, a pair of pole pieces secured thereto having upper and lower ledges facing each other, a voice coil disposed between said ledges symmetrically of said 55 pole pieces, a fixed armature extending downward axially of said coil between the upper ledges and terminating adjacent the lower ledges, a magnetic flux relay piece disposed in the space between said lower ledges and slightly spaced from 60 the lower end of said armature, a rigid shaft for said flux relay piece, at right angles to the axis of said coil, a bearing mount on said base for said shaft and a stylus clamped to said shaft.

6. A magnetic pickup comprising a base, a pole 65 piece, voice coil and fixed armature assembly thereon, a magnetic flux relay piece including an upstanding wing, a light shaft rigidly mounting said wing near one end thereof, bearing means supporting said shaft upon said base, and a stylus 70 clamped with respect to said shaft near the other end thereof.

7. A magnetic pickup comprising a base and a pole piece, voice coil and fixed armature assembly, a magnetic flux relay including an upstand- 75

ing wing, a light shaft rigid with said wing and extending forward therefrom, a stylus fixed with respect to said shaft, an upstanding post on said shaft and stop means laterally of said post to dampen and limit the movement of said wing between the armature poles.

8. A magnetic pickup comprising a base, a unit mounted on said base including a pair of pole pieces, a voice coil mounted therebetween and an armature in fixed relation between said pole pieces and extending into said coil, a shaft and bearings therefor mounted on said base, a magnetic flux relay piece attached to the end of said shaft and having an upstanding wing extending between the lower parts of said pole pieces to the neighborhood of the lower end of said armature, a stop piece rigid with said base and above said shaft and an upstanding post on said shaft having a flat upper end extending into a corresponding notch in said stop piece and damping and limiting the movement of said wing between said pole pieces, said shaft having a stylus clamped near the forward part thereof.

9. A magnetic pickup comprising a pole piece, a voice coil and an armature, said parts mounted in fixed relation to each other and a vibratory assembly including a non-magnetic shaft, a stylus near one end thereof and a magnetic flux relay piece at the other end thereof with respect to said stylus, said relay piece including a wing extending between said pole pieces and contiguous to said armature, the predominating portion of the mass of said vibratory assembly being said stylus.

10. A magnetic pickup comprising a base, an assembly fixed thereon including magnetic pole pieces, a voice coil therebetween and a fixed armature extending into said coil, a coacting magnetic relay assembly comprising a light tube of non-magnetic metal, rubber bushings thereon, bearings therefor affixed to said base, a stylus extending thereacross and clamped with respect thereto, and a magnetic flux relay piece comprising a shank frictionally fitted into the rear end of said tube and having an upstanding wing extending between said pole pieces to a point adjacent the armature.

11. The combination set forth in claim 10 in which a pin is fixed transversely of said tube and has an upstanding flattened end lodged in a notch in a metallic angle piece affixed to said base above said bearings.

12. In a magnetic pickup, the combination of a base having lateral stops, a U-shaped magnet supported thereon, a pair of pole pieces affixed to said base, a leaf spring reacting at its ends against said stops and exerting pressure on said U-shaped magnet to maintain its ends in contact with said pole pieces, said leaf spring being of width greater than the thickness of said magnet and having a longitudinal slit to determine an upper strap bowed outward above said magnet to retain the same against the bottom of the base.

13. In a magnetic pickup, a pole piece and armature assembly comprising a U-shaped pole piece, a non-magnetic metal bar affixed to one leg of said pole piece, and a fixed armature affixed to the edge of said bar and extending transversely of the legs of said U and magnetically spaced therefrom.

14. In a magnetic pickup, a magnetic flux relay assembly comprising a light metal tube, a pair of rubber bushings about the ends thereof, a screw in one end of said tube for clamping a stylus adapted to extend through apertures in said tube and a magnetic member having a shank

frictionally fitted in the other end of said tube and having an integral wing upstanding therefrom.

15. In a magnetic pickup, a magnetic flux relay assembly comprising a light metal tube, a pair of rubber bushings about the ends thereof, a set screw in one end of said tube for clamping a stylus adapted to extend through apertures in said tube and a magnetic member having a shank frictionally fitted in the other end of said tube and having an integral wing upstanding therefrom, and a positioning pin affixed transversely through said tube and having an upstanding flattened end in the plane of said wing.

16. In a magnetic pickup, a base, a magnet pole piece, coil and fixed armature assembly thereon, a vibratory assembly co-ordinated therewith and comprising a magnetic flux relay piece including a wing extending between said pole pieces and contiguous to said armature, a non-magnetic tube mounting said wing, bearings for said tube mounted on said base, a stylus transversely of said tube, means clamping said stylus between its ends, the ends of said stylus being of diameter and mass greatly reduced with respect to the median clamped portion thereof.

17. A magnetic pickup comprising a case having a removable metal cover thereon, a stylus carrying tube longitudinally of said case, a vibratory magnetic member mounted on said tube, pole pieces in said case correlated therewith, a stylus transversely through said tube, an aperture through said cover with which the upper end of said stylus is flush when properly positioned and a set screw through the forward end of said case for clamping said stylus with respect to said tube.

18. A magnetic pickup comprising a base having a cover, a magnet, an armature and a voice coil thereabout mounted on said base, a magnetic flux relay piece extending between said pole pieces and contiguous to said armature, a hollow shaft mounting said relay piece and having bearings affixed to said base, a stylus transversely through the forward bearing and through said shaft, said stylus having an enlargement contacting the upper portion of said forward bearing when positioned through a corresponding aperture in said cover and a set screw through the forward end of said base clamping said stylus in position.

19. The method of assembling a magnetic pickup of the type comprising pole pieces, a fixed armature and a flux relay piece extending between said pole pieces and adjacent said armature, said method comprising the centering of said flux relay piece between the pole pieces by straddling said relay piece with a fork fitting snugly between said pole pieces, clamping the mount for said flux relay piece in thus centered position, mounting the armature piece in contact with said flux relay piece, and then interposing a shim of appropriate thickness between the pole piece and the armature mount to elevate said armature with respect to said flux relay piece to determine the desired air gap between the stationary armature and the flux relay piece.

20. A magnetic pickup including a magnet having pole pieces and having a fixed armature, a voice coil encircling part of the magnetic circuit, a magnetic flux relay piece associated with said pole pieces and said armature, a stylus, a shaft adjacent to said relay piece and rigid therewith rigidly connected to an end of said shaft for imparting vibration to the relay piece to cause the alternations and variations of magnetic flux.

through said coil, said armature being concave at the part contiguous to said flux relay piece for reduction of the air gap therebetween in a direct ratio with the amplitude of vibration of said flux relay piece.

21. A magnetic pickup including a magnet having pole pieces and having a fixed armature, a voice coil encircling part of the magnetic circuit, a magnetic flux relay piece associated with said pole pieces and adjacent one

end of said armature, a shaft adjacent to and carrying said relay piece, a stylus at an end of said shaft, said armature having a hollowed out conformation in the region of said flux relay piece to cause the latter to approach one or the other lateral portions of said armature and reduce the air gap in a direct ratio with the amplitude of vibration of said relay piece.

MAXIMILIAN WEIL. 10
